UNITED STATES PATENT OFFICE.

EPHRAIM GILLAM, OF COLUMBUS, OHIO.

DESIGN FOR A TOY WHEELBARROW.

56,003.

Specification for Design.

Patented Aug. 10, 1920.

Application filed June 5, 1919. Serial No. 302,071. Term of patent $3\frac{1}{2}$ years.

To all whom it may concern:

Be it known that I, EPHRAIM GILLAM, a citizen of the United States, residing at Columbus, in the county of Franklin and State of Ohio, have invented a new, original, and ornamental Design for a Toy Wheelbarrow, of which the following is a specification, reference being had to the accompanying drawing, forming part thereof.

The figure is a perspective view of a toy wheelbarrow, showing my new design.

I claim:

The ornamental design for a toy wheelbarrow, as shown.

EPHRAIM GILLAM.
